Attorney.

UNITED STATES PATENT OFFICE.

GEORGE EDWARD KINCH, OF QUIRINDI, NEW SOUTH WALES, AUSTRALIA.

PAN-CLOSET CABINET.

1,343,830.

Specification of Letters Patent. Patented June 15, 1920.

Application filed March 28, 1917. Serial No. 158,126.

To all whom it may concern:

Be it known that I, GEORGE EDWARD KINCH, subject of the King of Great Britain and Ireland, residing at "The Poplars," Quirindi, New South Wales, Australia, have invented certain new and useful Improvements in Pan-Closet Cabinets, of which the following is a specification.

This invention relates to pan closet cabinets with lift-up seats, and consists in means for effecting closure and opening of the seat lid automatically and holding said lid in open position while the cabinet is in use.

15 The cabinet comprises an open top casing preferably constructed of sheet metal, a seat mounted with hinges thereon, a counterbalanced folding lid mounted on the seat, a footboard carried on levers fulcrumed on 20 the casing and mechanically connected with said lid, and a movable sill on the front edge of the seat mechanically connected with said footboard. The casing is open below and is fitted with a ventilator and a spring 25 grip for holding the pan in a fixed position.

In the accompanying drawings, Figure 1 is a side elevation of the cabinet as it appears when closed; Fig. 2 a side elevation of the same as it appears when the seat is 30 lifted; Fig. 3 a longitudinal vertical section of the same with the seat closed and the seat lid raised; and Fig. 4 a perspective view corresponding with Fig. 1.

The case 1 is constructed of sheet metal 35 with wire roll top edges; it is open bottomed and open topped and is fitted with pan holding springs 2 and a ventilator connection 3 at rear side. The seat panel 4 covers the case and is hinged thereto as shown at 40 5, so that it may be lifted up as shown in Fig. 2 to facilitate removal and insertion of the pan. 6 are frame battens which brace the seat and offer support at their forward extremities for the sill bar 7 which is pivotally mounted by side lugs 8 to the seat panel 4 so that it may swing upward as 45 shown in Figs. 1 to 4. The lid 9 is fixed on a back batten 10 which is hinged at 11 to a frame batten 12 fixed across the back 50 of the seat panel 4. The lid 9 is counterbalanced by weights 13 hung on rearwardly projecting arms 14 which are screwed to the ends of the lid batten 10. A rocking footboard 15 across the front of the case is carried on rock levers 16 which are fulcrumed to said case at 17. The rear ends of these

rock levers are connected by links 18 to lugs 19 on the lid batten 10. 21 are push rods freely slidable in guides 22 fixed on the front of the case 1. The lower ends 60 of the rods 21 are loosely connected to the inner edge of the footboard 15, and their upper ends contact with the underside of the sill 7, and they operate to cant up the sill 7 when the lid 9 is closed and the footboard 15 is in the raised position shown in Figs. 1 and 4. The weight of the lid 9 acting through the links 18 and levers 16 holds the footboard in the raised position. The weight of a person resting on the sill 70 7, acting through the push rods 21, forces the footboard down and thereby rocks the levers 16 and by means of the link 18 holds the lid 9 in the raised position as shown in Fig. 3. 23 is an apron piece fixed below 75 the front edge of the seat panel, serving to close the upper part of the case front. The ends of the batten 10 act as stops for the links 18 and so prevent the lid 9 being forced too far backward when opened. 80

The seat may be swung open upwardly upon its hinges 5, thus fully opening the top of the case 1 as shown in Fig. 2. When the seat is down on the case, the weight of a person standing or resting on the footboard 85 15, acting through the levers 16 and links 18, lifts the lid 9, as shown in Fig. 2. Weight resting on the sill 7 acting through the push rods 21 holds the footboard 15 down, and so maintains the lid in the fully open 90 position as shown in Fig. 3. Upon release of weight and pressure from the footboards 15 and sill 7, the lid closes by gravity (see Fig. 4), the counterweights 13 preventing slamming and insuring silent closing. 95

What I claim as my invention and desire to secure by Letters Patent is:—

1. The combination with a pan closet cabinet having a seat and a hinged seat lid, of a member pivotally mounted at the front 100 edge of said seat, means operated by depression of said member for positively raising said lid, and battens secured to said seat serving both to brace the same and to firmly support the pivoted member in depressed 105 position.

2. The combination with a pan closet cabinet of a seat hingedly connected to said cabinet, a seat lid hingedly connected to said seat, rods slidably mounted at the front of 110 the cabinet, a member pivotally carried by said seat at the front edge thereof, said

member being unconnected to said rods but positioned in operable relation to the upper ends thereof by movement of the seat into normal lowered position, levers operated by the lower ends of said rods when depressed by said member, and connections between said levers and the seat lid for opening the latter.

3. A pan closet consisting of a case open at the top, a seat panel hinged to the back of said case and adapted to fold down thereon, frame battens mounted on the under-side of said panel and bracing the same, the forward ends of said battens projecting beyond the end of said seat, a gravity closed lid hinged at its rear end to the rear part of said seat, a canting sill hinged to the front of said seat and supported in its operative position by said forward projections of said battens, a canting footboard, levers carrying said footboard and fulcrumed on the side of said case, press rods between said sill and said footboard adapted to depress the footboard when the sill is depressed, and link connections between said levers and said lid.

4. A pan closet consisting of a case open at the top, a seat panel hinged to the back of said case and adapted to fold down thereon, frame battens mounted on the under-side of said panel and bracing the same, the forward ends of said battens projecting beyond the end of said seat, a gravity closed lid hinged at its rear end to the rear part of said seat, rearwardly projecting arms on said lid, counterbalancing weights suspended from said arms, a canting sill hinged to the front of said seat and supported in its operative position by said forward projections of said battens, a canting footboard,

levers carrying said footboard and fulcrumed on the side of said case, press rods between said sill and said footboard adapted to depress the footboard when the sill is depressed, and link connections between said levers and said lid. 45

5. The combination with a pan closet cabinet of a seat hingedly connected to said cabinet, a seat lid hingedly connected to said seat, a pivotally mounted member at the lower front part of the cabinet, means operated by said member for raising the seat lid, means movably mounted at the front of the cabinet and arranged when moved to operate the first named means, and a member pivotally mounted upon the seat and arranged to be positioned in operative relation to the second named means by movement of the seat into normal lowered position. 50

6. The combination with a pan closet cabinet of a seat hingedly connected thereto, a seat lid hingedly connected to said seat, a member pivotally mounted at the lower front part of the cabinet, means operable by 55 said member for positively raising the seat lid, means movably mounted at the front part of the cabinet, arranged when moved to operate said pivoted member, and a second pivoted member mounted on the seat 60 at the front edge thereof and arranged to be positioned in operative relation to the second named means by movement of the seat into normal lowered position.

In testimony whereof I have affixed my 75 signature in the presence of two witnesses.

GEORGE EDWARD KINCH.

Witnesses:

WILLIAM POLLOCK,
A. E. Scott.
